(57) **CLAIM**

The ornamental design for a tool for fixing a reducer for a sprinkler in a sidewall, as shown and described.

DESCRIPTION

FIG. 1 is a perspective view of a tool for fixing a reducer for sprinkler in a sidewall showing new design;

FIG. 2 is a front view thereof;

FIG. 3 is a rear view thereof;

FIG. 4 is a left-side view thereof;

FIG. 5 is a right side view thereof;

FIG. 6 is a top plan view thereof;

FIG. 7 is a bottom view thereof; and,

FIG. 8 is another perspective view thereof.
